UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

GLASS-POLISHING MACHINE AND HOLDING CHUCK.

Application filed October 2, 1922. Serial No. 591,782.

To all whom it may concern:

Be it known that I, CHARLES W. DAKE, a citizen of the United States, residing at Chicago, in the county of Cook and State 5 of Illinois, have invented a certain new and useful Improvement in Glass-Polishing Machines and Holding Chucks, of which the following is a specification.

My invention relates to a polishing machine for polishing glass headlight reflector bowls and the like and is especially concerned with the chuck adapted to hold the bowl on the spindle and with the polishing pad used to perform the polishing act.

One object of my invention is to provide a new and improved form of support for a polishing pad adapted to polish the inside of headlight bowls. Another object is to provide a new and improved form of pneumatic chuck which will hold the bowl and permit polishing of the inside thereof. Other objects will appear from time to time in the specification.

My invention is illustrated more or less 25 diagrammatically in the accompanying drawing wherein:

Fig. 1 is a section through the chuck and the work;

Fig. 2 is an end elevation of the work 30 showing the polishing element in place.

Like parts are indicated by like characters in the drawings.

A is a supporting base adapted to be mounted on legs such as A'. A² is a bearing bracket upwardly projecting from the base A and terminating in a bearing A³ carrying the spindle or shaft A⁴. This spindle or shaft carries at its outer end a bowl-like chuck A⁵ which chuck terminates in an enlarged flange A⁶, having a packing member A⁷ thereon. The shaft A⁴ is apertured as at A⁸ so that air may be sucked through the shaft from the interior of the chuck A⁵.

I provide any suitable air exhaust or 45 suction means, not herein shown, the details of which form no part of the present invention, for exhausting through the passage A⁸ the air trapped between the chuck and the reflector bowl contained therein.

B is a reflector bowl, in this case made of 50 glass. It is contained within the chuck A⁵ engaging adjacent its outer periphery the backing member A⁷ which makes an airtight joint. B' is a plug closing the aperture B² in the reflector bowl. This plug is guided

by the pin B³ which loosely slides in the hole A⁸ without plugging it and is held against the base of the bowl so as to close the opening by means of the spring B⁴. This spring is strong enough to insure a 60 close snug fit of the plug with the bowl and is also strong enough so that the air pressure tending to seat the bowl in the chuck will not unseat the plug. The spring seated plug is necessary in this connection to conform or compensate for slight inaccuracies in the size of the bowl and also to permit expansion and contraction of the glass bowl without breaking and without dropping the 65 bowl from the chuck.

C is a bracket extending upwardly from base A. Pivoted thereon and adapted to swing across into line with the chuck is a supporting arm C'. This arm terminates in a yoke C² in which is trunnioned the sleeve 70 C³. C⁴ is a polishing pad mounted for rotation in the sleeve C³ and having a flexible, pneumatically extended polishing sheet or integument C⁵ which may be inflated through the air valve C⁶ to proper contour 75 and pressure to cause the polishing surface to conform to the contour of the work. C⁷ is a lever arm which may be weighted to increase the pressure of the polishing element.

It will be noted that the plug closing the 80 opening B² is on the side of the bowl removed from the polishing pad. This permits the pad to extend clear through into the opening and insures that every portion of the reflector bowl may be polished, there being just sufficient clearance between the plug and the polishing pad to permit this.

No means are shown for driving or rotating the polishing pad other than its frictional engagement with the reflector bowl. 85 Experience shows that as the reflector bowl or work is rotated the pad will also rotate, and the fact that the pad and the work rotate about different axes insures a proper polishing of the surface.

It will be evident that while I have shown in my drawing an operating device, still many changes might be made both in size, shape and arrangement of parts without departing materially from the spirit of my invention, and I wish that my drawing be regarded as in a sense diagrammatic.

I claim:

1. A pneumatic chuck for holding reflector bowls and the like comprising a cup 110

adapted to enclose the work, a packing element interposed between the mouth of the cup and the work, yielding means carried by the cup for closing an aperture in the work, a fluid conductor element adapted to be connected to an exhausting means, and having a fluid passage connecting with the cup.

2. A pneumatic chuck for holding reflector bowls and the like comprising a cup adapted to enclose the work, a packing element interposed between the mouth of the cup and the work, yielding means carried by the cup for closing an aperture in the work and a fluid conductor element adapted to be connected to an exhausting means, and having a fluid passage connecting with the cup, the aperture closing means comprising a plug, a guide member therefor and a spring adapted to thrust the plug outwardly against the work.

3. A polishing machine for glass bowls and the like comprising a cup adapted to enclose a portion of the bowl, means for closing an aperture in the bowl, and a fluid conductor element adapted to be connected to an exhausting means, and having a fluid passage connecting with the cup, the aperture closing means being removed from the inner surface of the bowl, and a polishing element adapted to project into the bowl to polish it.

4. A polishing machine for glass bowls and the like comprising a cup adapted to enclose a portion of the bowl, means for closing an aperture in the bowl and a fluid conductor element adapted to be connected to an exhausting means, and having a fluid passage connecting with the cup, the aperture closing means being removed from the inner surface of the bowl, and a polishing element adapted to project into the bowl and polish it, the polishing element extending into the aperture in the bowl but out of contact with the closing means.

5. A reflector bowl grinding machine comprising a rotating shaft, a cup carried thereby adapted to contain the bowl and means for holding the bowl in position therein, a bracket extending upwardly and outwardly adjacent the cup, an arm pivoted thereupon, to rotate about an axis inclined to the axis

of rotation of the bowl, and adapted to swing into line with the cup, a polishing pad bearing element pivoted adjacent the end of said arm to rotate about an axis perpendicular to the axis of rotation of the arm, a polishing pad pivoted in said bearing to rotate about an axis perpendicular to the axis of rotation of said bearing, and adapted to rotate as a result of the rotation of the bowl with which it is engaged, the arm being positioned and proportioned to hold said pad against said bowl eccentrically of the axis of rotation of the bowl.

6. A chuck for holding headlight reflector blanks and the like comprising a bowl-shaped member, a packing ring about the mouth thereof on the inside adapted to engage the work, a valve plunger adapted to engage and close a central aperture in the work, a guide rod for said plunger, yielding means for holding the plunger against the work and a fluid conductor element adapted to be connected to an exhausting means, and having a fluid passage connecting with the cup.

7. A chuck for headlight reflector bowls comprising a cup adapted to enclose the bowl, a packing ring interposed between the mouth of the cup and the body of the bowl, a spring-held valve adapted to yieldingly engage the bowl and close an opening therethrough, a spring therefor, a fluid conductor adapted to be connected to an exhausting means, and having a fluid passage connecting with the cup, the tension on the valve holding spring being sufficient to prevent opening of the valve by atmospheric pressure while permitting expansion and contraction of the bowl without unseating the valve.

8. A pneumatic chuck for holding reflector bowls and the like, comprising a cup adapted to inclose the work, yielding means carried by the cup for closing an aperture in the work, and a fluid conductor element adapted to be connected to an exhausting means, and having a fluid passage connecting with the cup.

Signed at Chicago, county of Cook and State of Illinois, this 28th day of September, 1922.

CHARLES W. DAKE.
